UNITED STATES PATENT OFFICE

2,226,479

APPARATUS FOR MECHANICALLY AND ELECTRICALLY CONNECTING CONDUCTORS CARRYING HIGH FREQUENCY CURRENTS

Wolfgang Pupp, Berlin-Kopenick, Germany, assignor to Julius Pintsch Kommanditgesellschaft

Application January 22, 1938, Serial No. 186,454
In Germany February 8, 1937

7 Claims. (Cl. 178—44)

This invention relates to apparatus for mechanically and electrically connecting conductors carrying high frequency currents, and concerns in particular apparatus for transmitting oscillation energy of ultra-high frequency (energy-transmitting cables), such as are employed, for example, between oscillation generators and loading resistances.

The primary object of the present invention is to provide apparatus by means of which it is possible to form a mechanical and electrical connection between two members carrying high frequency energy and to reduce the influence of contact resistance between these members.

The present invention provides apparatus for mechanically and electrically connecting conductors carrying high frequency current, in particular energy-transmitting cables, comprising a member connecting points which are located at nodes of the current flowing through the conductors.

A particular embodiment of the present invention provides for the tuning of a conductor system, preferably a concentric energy-transmitting cable, by means of a movable member mounted thereon, in particular a piston, having a length of $\lambda/4$, where λ is the operating wave length. The member employed in a concentric energy-transmitting cable is preferably a hollow body closed on one side and having a length of $\lambda/4$. With such a construction no current flows between the edges of the tuning member and the energy-transmitting cable. Thus the effect of contact resistances, which may be formed, for example, by oxidation of the metal parts in ultra-short wave apparatus which is frequently located in the open air, or by loose contacts, is completely eliminated.

In a particular example of carrying the present invention into effect which relates to concentric energy-transmitting cables having a central conductor, the bore of the tuning member slides over the central conductor of the energy-transmitting cable, while the outer surface of the member slides inside the outer conductor of the cable, the length of the member being equal at least to one quarter of the operating wave length.

If the wave length employed with such an arrangement is not a fixed quantity, the currents flowing at the junction of the tuning member and the cable are still considerably smaller than they would be if the member was not tuned. If, however, the wave length is a fixed quantity the

current flowing at the said junction when tuned to resonance is completely reduced to zero.

According to a further embodiment of the present invention the elasticity of the wall of the tuning member is such that the wall adapts itself to the shape of the energy-transmitting cable. No additional component parts, such as contact springs, tightening wedges and the like, are required for this purpose, but the wall of the member is provided with a plurality of longitudinal slots, six being a suitable number. The spring action of the slotted wall extends over a length which is considerably greater than the diameter of the member and the contact points are located at the ends of the leaf springs thus formed, so that efficient movement of the tuning member can be effected.

In order that the present invention may be clearly understood specific embodiments thereof will be described, by way of example, with reference to the accompanying drawings, but it will be understood that the invention is in no way restricted to the specific details given below and that many modifications of the said details may be effected within the scope of the appended claims.

In the drawings:

Figure 1 is a diagram showing the application of the present invention to a parallel conductor cable;

Figure 2 is a sectional elevation of a concentric energy-transmitting cable tuned by a member constructed in accordance with the present invention;

Figure 3 is a sectional elevation of a concentric energy-transmitting cable tuned in accordance with the present invention and connected to a plurality of radiating systems; and

Figure 4 is a sectional view of a concentric energy-transmitting cable provided with a tuning member of variable length.

Referring to Figure 1, a parallel conductor cable (Lecher wire) 1 is connected to a high frequency electric generator 1a. This cable is tuned by means of a short-circuiting loop 2, the limbs of which are of the length $\lambda/4$ along the axis of the cable, where λ is the wave-length of the transmitted current. The limbs are preferably constructed in the form of tubes which slide over the two conductors. In this manner the current flowing between the short circuiting loop and the energy-transmitting cable (at 3) is reduced to zero.

Figure 2 shows a further example of the present invention, in which a concentric cable

comprises an outer conductor 4 and a central conductor 5. An oscillation generator is connected to the cable at 6. The tuning member 7 is constructed in the form of a piston the length of which is $\lambda/4$. The outer conductor 71 and the inner conductor 70 of the member 7 are electrically connected together, for example, by soldering or by constructing the piston in a single piece. The parts 70 and 71 are provided with slots 72 in order to increase the spring action. The sliding of the piston in the direction of the axis may be effected in various ways, a simple manner being with the aid of a handle 8 projecting through a slot in the outer conductor 4. In particular, the piston may be moved through micrometer action by which the position can accurately and uniformly be varied, and adjusting mechanism can be provided with a scale divided into wave lengths or frequencies.

In the diagram shown in Figure 3 the present invention is applied to an energy-transmitting cable connected to a plurality of radiating systems, such as are fully described in United States of America patent application Serial No. 129,218.

The outer conductor 4 and the inner conductor 5 are connected to a source of high frequency energy which is radiated through the individual radiating systems 9 which are connected to the energy-transmitting cable by means of gaps therein. A tuning piston 7 having a length of $\lambda/4$ is again provided for tuning the cable. As is shown in this example, it is not essential that the parts 71 and 70 should abut directly against the outer conductor and the inner conductor respectively of the energy-transmitting cable, because the contact resistance between the tuning piston and the energy-transmitting cable is negligible owing to the fact that there is no current flowing at the junction of the cable and the piston.

It may be desirable when the operating wave length of the circuit is not of fixed value to provide a set of tuning members of various sizes, or to render the length of the tuning member variable. It is thus possible to vary the effective lengths of the tuning piston in contact with the inner conductor and with the outer conductor either separately or simultaneously. A constructional example of this embodiment of the present invention in which the effective lengths may be varied simultaneously is shown in Figure 4. The outer conductor 4 and the inner conductor 5 of the energy-transmitting cable are connected to a source of high frequency energy. The tuning member 12 is provided with tubular component parts 13 and 14 which extend into flexible parts 13a and 14a, these being electrically conductive at least along the surfaces. The flexible parts 13a and 14a are connected to metal rings 15 and 16, which are rigidly connected together by ceramic parts 23 of either disc or rod formation. The member 12 is provided with a tubular extension 24 having a screw thread along the outer surface. The distance of the rings 15 and 16 from the part 12 may be reduced by turning a nut 25 which engages the screw threaded extension 24, since the ceramic parts 23 are connected to parts 27, 28 associated with the nut 25 by rods 26. The arrangement is such that the nut 25 may be turned without the rods 26 being rotated because the part 27 of the nut 25 rotatably engages the ring 28 connected to the rods 26.

The present invention is not limited to the examples described and illustrated, and may be applied, for example, in all cases where it is de-

sired to form joints, connections, plug contacts and points of abutment of assembled energy-transmitting cables. According to the present invention, such points are located in such a position that zero current flows therein. In this manner loss of energy or excitation of the outer side of the energy cable causing radiation through any existing slots is effectively prevented.

The invention may be employed with considerable advantage with the apparatus described and claimed in United States of America patent application Serial No. 129,218, and in particular in combination with the valves described and claimed in United States of America patent specification No. 2,128,233 and modifications thereof.

What I claim as my invention and desire to secure by Letters Patent of the United States is:

1. Apparatus for tuning conductors carrying high frequency currents, in particular energy-transmitting cables, comprising a connecting member which short-circuits said conductors at points located at nodes of the current flowing through the conductors, said connecting member being of a length along the axis of the conductors equal to at least one-quarter of the operating wave-length of the current flowing through said conductors.

2. Apparatus for tuning concentric energy transmitting cables having an outer conductor and a central conductor, comprising a hollow cylindrical member which is open at one end and which short-circuits the outer and central conductors of the cable at points located at nodes of the current flowing through said conductors, the said member being of a length along the axis of the conductor equal at least to one quarter of the operating wave-length of the current flowing through said conductors.

3. Apparatus for tuning concentric energy-transmitting cables having central conductors, comprising in combination a hollow cylindrical member which is open at one end and which short-circuits the conductors of the cable, the said member being of a length along the axis of the conductors equal at least to one quarter of the operating wave-length, and a plurality of longitudinal slots in the surface of the said member for effecting spring action between the said member and the concentric conductors.

4. Apparatus for tuning concentric energy-transmitting cables having an outer and a central conductor, comprising in combination a hollow cylindrical member which is open at one end and which short-circuits the outer and central conductors of the cable at points located at nodes of the current flowing through said conductors, the said member being of a length along the axis of the conductors equal at least to one quarter of the operating wave-length, and means for varying the position of the said member along the axis of said conductors.

5. Apparatus for tuning concentric energy-transmitting cables having central conductors, comprising in combination a hollow cylindrical member which is open at one end and which short-circuits the conductors of the cable, the said member being of a length along the axis of the conductors equal at least to one quarter of the operating wave-length, means for varying the position of the said member, and a plurality of longitudinal slots in the surface of the said member for effecting spring action between the said member and the concentric conductors.

6. Apparatus for tuning conductors carrying

high frequency current, in particular energy-transmitting cables, comprising a member which short-circuits the said conductors at points located at nodes of the current flowing through
5 said conductors and are of a length along the axis of the conductors equal at least to one quarter of the operating wave-length of the current flowing through said conductors, and means for varying the length of said member along the axis
10 of the conductors in accordance with variations in the operating wave-length of the current flowing through said conductors.

7. Apparatus for tuning concentric energy-

transmitting cables having an outer and a central conductor, comprising a hollow cylindrical member which is open at one end and which short-circuits the outer and central conductors of the cable at points located at nodes of the current flowing through the conductors, the said member being of a length along the axis of the conductors equal at least to one-quarter of the operating wave-length of the current flowing through said conductors, said outer conductor being connected to a plurality of individual radiator systems. 5
